UNITED STATES PATENT OFFICE.

ALBERT L. GOODENOW AND WILLIAM J. OWENS, OF UTICA, NEW YORK.

HOT-AIR FURNACE.

SPECIFICATION forming part of Letters Patent No. 231,559, dated August 24, 1880.

Application filed June 2, 1880. (Model.)

To all whom it may concern:

Be it known that we, A. L. GOODENOW and Wm. J. OWENS, citizens of the United States, residing at Utica, in the county of Oneida and State of New York, have invented certain new and useful Improvements in Hot-Air Furnaces; and we do hereby declare the following to be a full, clear, and exact description of the invention, such as will enable others skilled in the art to which it appertains to make and use the same, reference being had to the accompanying drawings, and to letters or figures of reference marked thereon, which form a part of this specification.

15 Similar letters indicate like parts.

Our invention relates to an improvement in the class of heating-furnaces; and it consists in the principles and details of construction hereinafter more fully described and shown.

20 Its object is to provide a furnace capable of both a direct and an indirect draft by means of a damper arranged in one of the flue-passages to the radiator, whereby the gases of combustion may be compelled to traverse the 25 radiator and part with their heat, thereby reducing the waste to the minimum; also, in providing a heat-regulator in connection with the radiator, and in providing an interchangeable connection with the chimney-flue from either 30 side.

In the drawings, Figure 1 is a sectional view of our furnace through the line $x-x$ of Figs. 5 and 6. Fig. 2 is a side elevation, showing the heat-regulator. Fig. 3 is a vertical section 35 through the line $y-y$ of Fig. 1. Fig. 4 is a transverse vertical section on line $z-z$ of Fig. 1. Fig. 5 is a detail view of the joint uniting the sections of the furnace.

A is an ordinary fire-pot, above which is a 40 dome, B. The top of this dome is surrounded by an annular radiator, C, connecting with the dome by two passages, D D', one on each side, and having two radial smoke-nozzles, E E', directly over the passages from the dome to the 45 radiator. In one of these passages, D', is placed a damper, F, and the smoke-pipe to the chimney-flue is connected with radiator-nozzle E on the same side. The opposite nozzle, E', is provided with a pivoted lid or heat-regulator, G, which may be operated by a cord or wire, P, attached to it and extending to any room in

the house, for the purpose of admitting cold air into the radiator and thus regulating the heat and draft.

The connection of the furnace with the chimney-flue is interchangeable, and may be from either side, by removing the damper F and the regulator G to corresponding positions on the opposite side.

Pan-shaped flue-boxes H H' are fixed in the 55 outer casing of the hot-air chamber, through the bottom of which the nozzles E E' of the radiator project, as shown in Figs. 1 and 5, thus enabling the pipe leading to the chimney-flue to be readily attached from the outside. 60

The handle a of the damper F also projects into the flue-box, enabling the damper to be readily and conveniently operated from the outside. The fire-pot and dome and the dome and radiator are united by the ordinary sand-joint L.

V is the main door, through which the fuel is introduced; V', the door leading to the opening beneath the grate, and V'' the door of the ash-pit. Suitable draft-dampers are provided 70 in each.

V is the main door, through which the fuel is introduced; V', the door leading to the opening beneath the grate, and V'' the door of the ash-pit. Suitable draft-dampers are provided 75 in each. The operation of our invention is as follows: The fire is started in the furnace, and the drafts in door V and damper F are opened. After the fire is sufficiently under way damper F is 80 closed, and the smoke and products of combustion pass from the dome through the flue D into the radiator C, where they divide and pass around both sides until they reach the exit-nozzle E, thence out into the chimney. 85 Being thus retarded and compelled to perform the long circuit through the radiator nearly all the heat is imparted to the radiator before they are finally discharged into the chimney-flue. At any time when it becomes necessary to lessen the draft and diminish the heat it can be 90 readily and easily accomplished without visiting the furnace by opening the regulator G by means of the wire or cord P and admitting cold air into the radiator.

We are aware that furnaces have been heretofore constructed having radiators in various positions.

We are also aware that it is not new to provide for both a direct and an indirect draft 100 into the chimney-flue by means of a damper or dampers arranged in the smoke-flues; but

we are not aware that a furnace having a dome whose top is surrounded by an annular radiator united to the dome by two opposite passages beneath and communicating with the 5 radial nozzles in the radiator, and one of which passages is provided with a damper, has been heretofore used; hence,

What we claim, and desire to secure by Letters Patent, is—

- 10 1. A furnace having a dome, B, whose top is surrounded by an annular radiator, C, connected with it by opposite flue-passages D D', situated beneath and leading into radiating nozzles E E', one of which passages, D, on the side of the direct exit-flue, is provided with a damper, F, substantially as and for the purpose described.
- 15 2. In a furnace provided with an annular radiator surrounding its dome, having opposite radiating nozzles and connecting with the dome by opposite flue-passages, one of which,

on the side of the direct exit-flue, is provided with a damper, the vertically-inclined heat-regulator G, located in the end of the radiator-nozzle opposite the direct exit-flue, whereby cold air may be admitted to the radiator, substantially as and for the purpose described.

25 3. In a furnace as described, the flue-boxes H H', fixed in the outer casing of the hot-air chamber, having the radiator-nozzles, which connect with the flue-passages D D', projecting through their bottom, all combined and operating substantially as described, and for the purpose set forth.

In testimony whereof we affix our signatures 30 in presence of two witnesses.

ALBERT L. GOODENOW.
WILLIAM J. OWENS.
